MEDICAL INSTRUMENT

Simon Abraham, Atlanta, Ga.

Application November 4, 1948, Serial No. 149,472

Term of patent 14 years

(Cl. D83—1)

To all whom it may concern:

Be it known that I, Simon Abraham, a citizen of the United States, residing at Atlanta, in the county of Fulton and State of Georgia, have invented a new, original, and ornamental Design for a Medical Instrument, of which the following is a specification, reference being had to the accompanying drawing, forming part thereof.

Fig. 1 is a front elevational view of a medical instrument embodying my new design;

Fig. 2 is a top plan view thereof; and

Fig. 3 is a side elevational view thereof.

I claim:

The ornamental design for a medical instrument, as shown.

SIMON ABRAHAM.
